WORK SUPPORT

Eugene J. Ray, Beverly, Mass., assignor to United
Shoe Machinery Corporation, Flemington, N. J.,
a corporation of New Jersey

Application May 26, 1943, Serial No. 488,484

16 Claims. (Cl. 12—126)

This invention relates to work supports intended to carry shoes in certain types of automatic shoe machines. An example of such a machine provided with a work support of this type is the subject matter of my co-pending application for Letters Patent of the United States, Serial No. 488,483, filed May 26, 1943.

The purpose of the machine mentioned above is to trim the perimeter of the outsole of a shoe, and the purpose of the work support is to hold a shoe containing a last upside down while the trimming operation is being performed.

For the sake of brevity the work support is hereinafter termed a "jack." One of the novel features of the jack is provided by a pair of members arranged to clamp the counter portion of a shoe widthwise and at the same time support the marginal extension of the outsole by direct engagement therewith. For this purpose the clamping members are formed and arranged to project into the rand crease. This feature not only locates the rand creases of successive shoes heightwise regardless of the heightwise dimensions of the heel parts of the lasts, but it also does away with a last pin and with sidewise tipping of a shoe if the socket in the heel part of a last is inclined sidewise, as some of them are, instead of being quite true.

Another novel feature is provided by a combination of members including a toe gauge and a pair of members arranged to clamp the body of the forepart of a shoe widthwise. For reasons related to the trimming operation of the machine above mentioned, the purpose of the toe gauge is to locate the toe ends of all shoes at a uniform distance from the turning axis of the jack, regardless of the lengths of the shoes.

Still another novel feature is provided by means for carrying the counter clamps and a heel end abutment toward and from the toe gauge. The heel end abutment serves not only to locate the counter of a shoe in the desired relation to the counter clamps but also to locate the toe of the shoe against the toe gauge.

The forepart clamps and the toe gauge are connected to a common operating member which, when moved in a direction to close the clamps, also retracts the toe gauge from the outsole far enough to insure clearance of the trimming cutter and the trimming gauges.

Other improvements provided by the invention are hereinafter described and illustrated in the drawings.

Referring to the drawings,

Fig. 1 is a side elevation, partly in section, of

a jack embodying the improvements to be described;

Fig. 2 is an elevation of the heel end of the jack;

Fig. 3 is a vertical section indicated by a line III—III in Fig. 1;

Fig. 4 is a plan view, partly in section, of a pair of members for operating the forepart clamps;

Fig. 5 is an elevation of parts by which the forepart clamps and the toe gauge are interconnected; and

Fig. 6 is a section of means for adjusting and locking the toe rest (see line VI—VI in Fig. 3).

All the operative parts of the jack are carried by a frame 10 affixed to a jack post 11. For the purposes set forth in the aforesaid application, Serial No. 488,483, the post 11 is mounted in a bearing member 12 in which it may turn and move up and down.

20 The shoe-engaging elements include a pair of clamping members 13, 13, a pair of clamping members 14, 14, a toe gauge 15, a heel-end abutment 16 and a toe rest 17. The members 13, 13 are movable toward and from each other to clamp the forepart of a shoe widthwise; the members 14, 14 are also movable toward and from each other to clamp the counter of the shoe widthwise; the toe gauge 15 is movable up and down for a purpose to be explained; the heel-end abutment 16 is movable toward and from the toe gauge; and the toe rest 17 is adjustable up and down.

35 The purpose of the toe gauge is to locate the toe end of a shoe in a predetermined relation to the turning axis of the jack. This relation places the center of the toe portion nearly, if not exactly, on the axis A—A of the post 11. For this purpose the gauge should occupy the position represented in dotted lines in Fig. 1, when it may be engaged by the body of the shoe without touching the marginal extension of the outsole 18. Once the shoe has been located by the toe gauge the latter should be depressed far enough below the outsole to clear the trimming cutter and the trimming gauges (not shown) of a machine of the type set forth in the aforesaid application.

40 The toe gauge is guided up and down by bosses 19, 19 in which grooves are formed to receive it, and by retaining studs 20, 20 extending through a slot 21 in the gauge. A lever 22 connects the gauge and a link 23 and is mounted on a fulcrum pin 24. The lower end of the link is connected to an arm 25 of a lever having two other arms 26 and 27 (Fig. 5). A tension spring 28 attached

to the arm 26 and anchored to the frame 10 maintains the toe gauge initially in its elevated position. This three-armed lever is affixed to a rock shaft 29 provided with an operating handle 30 which, when depressed, pulls down the toe gauge and closes the clamping members 13, 13. A ratchet wheel 31 affixed to the rock shaft is engaged by a retaining pawl 32 which serves to lock the gauge in its depressed position as represented in full lines in Fig. 1.

The arm 27 of the three-armed lever is utilized to impart clamping movement to the clamping members 13, 13. These members (Fig. 3) are thin flexible plates of spring steel and are curved lengthwise in the manner of semi-elliptic springs to insure contact of their ends with the body of the shoe. The flexibility of the plates enables the intermediate portions to be sprung toward the shoe when the clamping pressure is applied. These intermediate portions are affixed to the heads of cylindrical stems 33, 33 (Fig. 3) that provide for swiveling motion with respect to carriers 34, 34 in which the stems have bearings.

Each carrier 34 is carried by and has pivotal connection with a pair of parallel links 35, 36. The links 36 are provided with operating arms 37 which, when depressed, move the clamping members 13 toward each other with parallel and equal motion. The free ends of the arms 37 are lapped (Fig. 4). A stud 38 affixed to one of them extends through a slot 39 in the other, and this stud may be moved up and down by a telescopic link the lower end of which engages a stud 40 affixed to the arm 27. One part of the link (Fig. 3) comprises a rod 41, a tubular element 42 and a cap 43 screwed on the latter. The other part of the link comprises a stem 44 and a collar 45 affixed thereto. The stem extends into the tubular element 42 and through a hole in the cap. A compression spring 46 surrounding the stem abuts the collar and the cap to provide a resilient operating connection.

The effect of the connections above described is as follows: when the handle 30 is depressed to pull down the toe gauge it also pulls down the telescopic link by which the clamping members 13, 13 are closed against a shoe. If the downward movement of the handle is continued after the clamping members are arrested by the shoe, the cap 43 will slide along the stem 44 toward the collar 45, thereby producing supplemental deflection of the spring 46 which, in turn, will develop pressure of the clamping members against the body of the shoe.

The saddle of the toe rest is secured to a vertically adjustable post 47 on which rack teeth 48 are provided (Fig. 1). A boss on the frame 10 is provided with a bore for the post and with a recess for a pinion 49 with which the rack teeth mesh (Fig. 6). The pinion is mounted on a square portion of a rotatable stem 50 and has a square hole therefor to provide a spline connection which enables the stem to be shifted endwise for locking purposes. A locking arm 51 affixed to one end of the stem carries a short pin 52 arranged to enter any one of a series of holes 53 bored in the frame 10, but the pin may be withdrawn to clear the holes by shifting the stem against a compression spring 54 that normally maintains interlocked relation. A knob 55 at the opposite end of the stem is effective to turn the pinion as well as to withdraw the locking pin. In practice, the toe rest will be adjusted to locate the marginal extension of the sole about one-fourth inch above the clamping members 13, 13.

to enable the trimming gauge to run on the body of the shoe above the clamping members without being engaged by the latter.

The clamping members 14, 14 are movable toward and from the toe gauge in addition to being movable toward and from each other. These clamping members are curved lengthwise to enable their ends to bear on the counter portion of a shoe and they are inclined (Fig. 2) to enable their upper edges to enter the rand crease and support the marginal extension thereof by direct engagement therewith. A shoe and its last are thereby braced against tipping sidewise. The heel-end abutment 16 is also arranged to enter the rand crease (Fig. 1) and engage the marginal extension thereof. This group of three work-engaging members is carried by a pair of carriers 78 and a pair of parallel links 60, 60 the lower ends of which are connected to the frame 10 by pivots 61, 62. The pivot 61 is a rock shaft by which one of the links is rigidly connected with an arm 63. A tension spring 64 exerts a pull on the arm in a direction to retract the group of work-engaging members away from the toe gauge.

To maintain this assemblage in an operative position as represented in Fig. 1, the jack is provided with a ratchet wheel 65 and a retaining pawl 66. The ratchet wheel and a pinion 67 are both affixed to a shaft 68. The pinion engages a rack bar 69 arranged to be moved to and fro in bearings in the frame 10 by one of the parallel links 60 with which it is connected by a coupling member 70. The two retaining pawls 32 and 66 are connected by a tension spring 71 which maintains them normally against their respective ratchet wheels. A finger 72 formed on the pawl 32, and a finger 73 formed on the pawl 66 are both arranged to be engaged by a manual tripping member 74 connected to the frame 10 by a pivot 75 (Fig. 2) and having a handle portion 76. These parts are so related that the member 74 will trip the pawl 32 before tripping the pawl 66 and thus release the shoe from the forepart clamping members 13, 13 before releasing the parallel links 60, 60 to the retractive effect of the spring 64 (Fig. 2). The retractive movement of the parallel links is arrested by a stop 77 arranged to be engaged by the arm 63.

The upper ends of the parallel links 60, 60 are connected by the carriers 78, 78 and connecting pivots 79. The carriers are spaced one from the other to flank the counter portion of a shoe (Fig. 2) but they are connected by a cross bar 80 arranged to lie athwart the back of a shoe. One purpose of the cross bar is to brace the carriers against stresses incidental to clamping the counter portion. Another is to carry the heel-end abutment 16 affixed to it. The ends of the cross bar are affixed to pivot pins 81 which extend lengthwise of a shoe and through portions of the carriers 78. Each pin 81 carries a bell crank 82 and each of the latter carries one of the clamping members 14. Stems 83 formed on the latter have swivel bearings in the bell cranks.

The bell cranks are interconnected to equalize the movements of the clamping members toward and from each other. For this purpose, two levers 84 carried by the carriers 78 are provided with cooperative gear segments 85 and have operating connection with the bell cranks. Each connection includes a socket member 86, a stem 87 in telescopic relation thereto, and a compression spring 88. An operating arm 89, a ratchet wheel 90 and one of the levers 84 are all affixed to one of the

fulcrum pins 91 by which the levers are connected to the carriers 78. A retaining pawl 92 carried by one of the carriers is normally held against the ratchet wheel by a spring 93 to maintain the clamping effect set up by the arm 89.

In practice, a shoe about to be set up in the jack will contain a last 94, the outsole 18 will require trimming, and the heel will have been attached to satisfy usual routine in shoe factories. The purpose of the trimming machine in which this type of jack serves is to trim the perimeter of the outsole in the forepart and along both sides of the shank nearly to the breast line.

The preferred routine with regard to the jack is as follows: if the jack is not already loaded with a shoe the assemblage carried by the parallel links 60, 60 will be initially retracted from the toe gauge 15 as far as the arm 63 and the stop 77 will permit; the operating handle 30 will be elevated; the toe gauge will occupy its upper position; the forepart clamps 13, 13 will be open; and the counter clamps 14, 14 will also be open. The operator will first place the back of a shoe against the abutment 16 and then operate the arm 89 with only enough movement to clamp the counter of the shoe with moderate pressure. Next, while supporting the forepart in the right hand, he will place the left hand against the cross bar 88 or the abutment 16 and shift the adjustable assemblage toward the toe gauge until the shoe abuts the latter. At this stage, the toe rest 17 will insure slight clearance between the toe gauge and the marginal extension of the sole. Furthermore, the adjustable counter assemblage will be held against return movement by the pawl 66.

The operator may next depress the handle 30 to close the forepart clamps 13, 13, depress the toe gauge, and build up the clamping pressure against the forepart. Finally, the arm 89 may be moved further to increase the clamping pressure against the counter.

The foregoing routine fulfills the setting-up requirements. After the trimming operation has been performed, the jack returns to its initial position, whereupon the operator will first move the tripping member 74 to release both ratchet wheels 31 and 65. The spring 28 now opens the forepart clamps and raises the toe gauge, and the spring 64 retracts the counter assemblage and the shoe from the toe gauge. While supporting the instep portion of the shoe in the right hand, the operator may release the counter portion by retracting the retaining pawl 92 (Fig. 2) with the left hand.

Having thus described my invention, what I claim as new and desire to secure by Letters Patent of the United States is:

1. A shoe-supporting jack comprising a frame, a toe gauge mounted thereon, a pair of clamping members arranged to clamp the counter portion of a shoe widthwise, a heel-end abutment, carrying means by which said clamping members and said abutment are carried collectively toward and from said toe gauge, said carrying means being adjustably mounted on said frame, and means carried by said carrying means for moving said clamping members toward and from each other.

2. A shoe-supporting jack comprising a frame, a toe gauge mounted thereon, a pair of clamping members arranged to clamp the counter portion of a shoe widthwise, a pair of carriers on which said clamping members are mounted, parallel links having pivotal connections with said carriers and with said frame for carrying said clamping members toward and from said toe gauge,

and means carried by said carriers for moving said clamping members toward and from each other.

3. A shoe-supporting jack comprising a frame, a toe gauge mounted thereon, a heel-end abutment, carrying means mounted on said frame and constrained thereby to carry said abutment toward and from said toe gauge, clamping means carried by said carrying means and arranged to clamp the counter portion of a shoe widthwise, and clamping means arranged to clamp the forepart widthwise, the latter said clamping means being mounted on said frame apart from said carrying means.

4. A shoe-supporting jack comprising a frame, a toe gauge mounted thereon, a pair of carriers, a pair of clamping members mounted on said carriers for clamping the counter portion of a shoe widthwise, parallel links mounted on said frame and pivotally connected by said carriers to guide said clamping members toward and from the toe gauge, means mounted on said carriers for moving said clamping members toward and from each other, and means arranged to secure said links in various positions of angular adjustment.

5. A shoe-supporting jack comprising a frame, a pair of clamping members mounted thereon for clamping widthwise the forepart of an outsoled shoe, a pair of clamping members arranged to clamp the counter portion widthwise, means arranged to carry said counter-clamping members toward and from the forepart-clamping members, and a heel-end abutment carried by said carrying means to locate the counter portion with respect to said counter-clamping members.

6. A shoe-supporting jack comprising a frame, a toe gauge mounted thereon, parallel links pivotally connected to the frame, carrying means pivotally connecting said links, the links being arranged to carry said means toward and from the toe gauge, a pair of cooperative clamping members carried by said means and arranged to clamp the counter portion of the shoe widthwise, and means for moving said clamping members toward and from each other.

7. A shoe-supporting jack comprising a frame, a toe gauge mounted thereon, parallel links pivotally connected to the frame, a pair of carriers connecting said links, said carriers being spaced widthwise of a shoe and the links being arranged to carry them toward and from the toe gauge, a pair of cooperative clamping members carried by said carriers and arranged to support the heel end of an outsoled shoe by engaging opposite portions of the rand-crease extension, and interconnected operating means carried by said carriers for moving said clamping members equally toward and from each other.

8. A shoe-supporting jack comprising a frame, a toe gauge mounted thereon, a pair of members arranged to clamp the forepart of a shoe widthwise, a heel-end abutment, means arranged to carry said abutment toward and from the toe gauge, said abutment having a portion formed to enter the rand crease and engage the marginal extension thereof, and a pair of members carried by said carrying means to clamp the counter portion widthwise.

9. A shoe-supporting jack comprising a pair of members arranged to clamp the forepart of a shoe widthwise, a toe gauge, a frame on which said clamping members and the toe gauge are mounted, and operating means by which the

clamping members and the toe gauge are interconnected to shift the latter heightwise of a shoe when the clamping members are moved widthwise of the shoe.

10. A shoe-supporting jack comprising a pair of members arranged to clamp the forepart of a shoe widthwise, a toe gauge, a frame on which said clamping members and the toe gauge are mounted, an operating member also mounted on the frame, and means by which said clamping members, said operating member and the toe gauge are interconnected to retract the latter from a shoe when the operating member is moved to close the clamping members.

11. A shoe-supporting jack comprising a pair of members arranged to clamp the forepart of a shoe widthwise, a pair of members arranged to clamp the counter widthwise, means by which said counter members are carried toward and from said forepart members, a frame on which said forepart members and said carrying means are mounted, means arranged to restrain said forepart members against movement away from each other, means arranged to restrain said carrying means against movement to retract the counter members from the forepart members, and a member arranged to trip both of said restraining means.

12. A shoe-supporting jack comprising a toe gauge, a heel-end abutment, means for carrying said abutment toward and from the toe gauge, a pair of members arranged to clamp the forepart of a shoe widthwise, a frame on which said toe gauge, carrying means and clamping members are mounted, means arranged to restrain said clamping members against movement away from each other, means arranged to restrain said carrying means against movement to retract said abutment from the toe gauge, and a member arranged to trip both of said restraining means. 40

13. A shoe-supporting jack comprising a pair of members arranged to clamp a shoe widthwise, two pairs of parallel links by which said clamping members are carried toward and from each other, a frame on which said links are pivotally mounted, and operating means by which said links are constrained to equalize the movements of the clamping members.

14. A shoe-supporting jack comprising a pair of members arranged to clamp a shoe widthwise, 10 a pair of carriers therefor, the clamping members and the carriers having swivel connections, two pairs of parallel links by which said carriers are carried toward and from each other, a frame 15 on which said links are pivotally mounted, and operating means by which said pairs of links are interconnected to move the clamping members toward and from each other.

15. A shoe-supporting jack comprising a frame 20 arranged to turn about an axis, a toe gauge arranged to locate the toe portion of a shoe in a predetermined relation to said axis, means arranged to clamp the counter portion widthwise, adjustable means arranged to carry said clamping means toward and from the toe gauge, means arranged to clamp the forepart widthwise, and means arranged to retract the toe gauge from engagement with the shoe.

16. A shoe-supporting jack comprising a heel-end abutment and a pair of counter clamps 25 arranged to form a group, a toe rest and a pair of forepart clamps arranged to form another group, carrying means on which one of said groups is mounted, a frame on which the other one of said groups is mounted, said carrying means being adjustably mounted on said frame and constrained thereby to carry its group toward and from the other, and means arranged to operate said clamps. 35

EUGENE J. RAY.
